UNITED STATES PATENT OFFICE

168,998

COMBINED DISPLAY STAND AND BASE

Sidney H. Horwitz, Shaker Heights, Ohio

Application November 7, 1952, Serial No. 22,190

Term of patent 14 years

(Cl. D80—9)

To all whom it may concern:

Be it known that I, Sidney H. Horwitz, a citizen of the United States and residing at Shaker Heights, in the county of Cuyahoga and State of Ohio, have invented a new, original, and ornamental Design for a Combined Display Stand and Base, of which the following is a specification, reference being had to the accompanying drawings, forming a part thereof.

In the drawings:

Fig. 1 is a perspective view of a combined display stand and base, showing my new design;

Fig. 2 is a top plan view;

Fig. 3 is a side elevational view;

Fig. 4 is a rear elevational view; and

Fig. 5 is a front elevational view thereof.

I claim:

The ornamental design for a combined display stand and base, substantially as shown and described.

SIDNEY H. HORWITZ.
